TRAIN DISPATCHING SYSTEM FOR RAILROADS

Filed April 15, 1927

FIG. 1

UNITED STATES PATENT OFFICE

OSCAR H. DICKE, OF ROCHESTER, NEW YORK, ASSIGNOR TO GENERAL RAILWAY SIGNAL COMPANY, OF ROCHESTER, NEW YORK

TRAIN DISPATCHING SYSTEM FOR RAILROADS

Application filed April 15, 1927. Serial No. 184,013.

This invention relates to train dispatching systems of the wayside signal indicating type, and more particularly to means for OS-ing the conditions of traffic of such systems.

The term OS-ing is used by railway signal engineers to denote the report of a train location or passage with respect to a certain point on a railway system and this term is used herein to signify the indication automatically transmitted to a dispatcher's office as to the condition of occupancy of a certain track circuit or group of track circuits. In order to economically indicate at a dispatcher's office the condition of occupancy of a large number of track circuits, it is necessary to transmit the indicating conditions as to occupancy of a large number of such track circuits over a single medium, such as a single line circuit. The chief problem that presents itself in this connection centers around the fact that not only is it possible that several track circuits will be entered upon by different trains at exactly the same time, but that such coincidence is quite probable. In view of this fact, it is not practicable to transmit a large number of OS signals over the same line wire by distinctive codes, as they are ordinarily understood, because if two trains would enter different track circuits at about the same time a jumbled up code, or series of impulses, the meaning of which could not be deciphered, would be transmitted.

In view of the above and other important considerations, it is proposed in accordance with the present invention to use a single line circuit for transmitting OS signals to indicate the occupancy of a large number of track circuits, and indicate other local conditions, such as, positions of track switches, indicating conditions of signals and the position of drawbridges, derails and the like, by transmitting distinctive frequencies from these points over such line circuit to dis-

tinctive frequency responsive relays or indicators. In order to make it possible to transmit an extremely large number of distinctive indications over a single line circuit it is proposed, as a more specific feature of the present invention, to employ relays or indicators of the mechanically tuned reed type each of which includes electro-magnetic actuating means which has its winding tuned to the same frequency. By an arrangement of this kind the indicators are very selective and a very large number of distinctive indications may be transmitted over the same line circuit.

Other objects, purposes and characteristic features of the invention will in part be apparent from the drawings, and in part be pointed out in the specification hereinafter.

In describing the invention in detail, reference will be made to the accompanying drawings in which:

Fig. 1 shows a portion of a railway track lay-out illustrating a single track and a passing siding, together with a dispatcher's tower in which indicators embodying the present invention corresponding to the track relays shown at such passing siding have been illustrated in a miniature track layout;

Fig. 2 shows a plan or front view of the panel of the miniature track layout illustrating an indicator of the mechanically tuned reed type forming a part of the equipment in the dispatcher's office;

Fig. 3 is a partial sectional view of the indicator shown in Fig. 2 taken on the line 3—3, as viewed in the direction of the arrows of Fig. 2;

Fig. 4 illustrates a combined transformer and interrupter for changing direct current into alternating current of a predetermined frequency and for inducing a voltage of such frequency in an insulated coil contained in a line circuit; and

Fig. 5 shows a modified form of the inven-

tion in which a vibratory reed is adapted to close an energizing circuit for an indicating lamp.

Referring to Fig. 1 of the drawings the dotted rectangle DO conventionally indicates a dispatcher's office in which is contained suitable control apparatus for operating the switch machines and signals at a number of distant passing sidings of a rail-way system, which apparatus has not been specifically shown, but of which the control levers LE and LW have been indicated in this dispatcher's tower DO. The switch machines SMW and SME conventionally shown are used for operating the track switches 8TS and 1TS, and are controlled by suitable control circuits conventionally illustrated by dotted lines 6 and 9 in accordance with the energized condition of the control relays ZW and ZE respectively; and these control relays ZW and ZE are controlled from the dispatcher's office DO by any suitable means, which has been conventionally shown by the dotted lines 40 and 41, all as more specifically shown in my prior application Ser. No. 180,475 filed April 2, 1927, or as shown in the application of S. N. Wight Ser. No. 120,423 filed July 3, 1926.

In this dispatcher's tower is contained a miniature track layout, preferably suitably engraved on a large panel 10, having holes therein through which the ends of the tuned reeds of the various track circuit indicators project, the location of each indicator corresponding to that of the track circuit controlling the same. In the particular arrangement shown only six such indicators have been illustrated, which indicators have been designated 7I, 7DI, 1I, 8I, 2DI and 2I.

Each of these indicators comprises a U-shaped core 11 constructed of laminated transformer iron, to which core is suitably secured, as by a screw 12, a reed 13; and on this core is contained a coil or winding 14 which has a condenser C connected there-across, which condenser electrically resonates the winding 14 to the same frequency as the natural period of vibration of the reed 13. This core 11 is secured to the back 50 of the panel 10 in any suitable manner as by the screws 15 shown. The reed 13 is preferably made of permanent magnet steel and preferably has a spring 13^a for properly tuning this reed suitably riveted thereto. This reed 13 is preferably magnetized, so that it is attracted when current flows in one direction and repelled when current flows in the opposite direction.

The particular distant passing siding illustrated in Fig. 1, is one in which a sufficient number of signals have been provided for controlling the entrance and departure of trains into and out of both ends thereof. In the particular arrangement shown the 65 west end of the siding has its track rails

insulated by insulating joints 20 so as to form a detector or fouling track circuit including the detector track relay 7DT and the track battery 21; and at east end of this passing siding in a similar way has the track rails insulated by insulating joints 23, so as to form another detector track circuit which includes the detector track relay 2DT and the track battery 24. The main track of the passing siding is provided with a track circuit including track relay 1T, and a track battery 25; and the side track of the passing siding is track circuited and includes a track relay 8T and a track battery 26. At the east end of the passing siding are two starting signals 2 and 2D which govern the movement of the traffic out of the passing siding into the single track section in an easterly direction, and at this same end is provided a main entrance signal 1 and a take siding signal 1D. In the same way, the starting signals at the west end of the passing siding have been designated 7 and 7D respectively, and the main entering signal has been designated 8 and the take siding signal has been designated 8D. These various signals are preferably jointly controlled in accordance with traffic conditions ahead and in accordance with the normal or reverse energized or the deenergized conditions of the control relays ZW and ZE, which control relays are controlled by the dispatcher as already mentioned. Although no specific circuits for controlling these signals at the west and east end have been shown it is desired to be understood that they may be controlled in a manner as shown in either of the two prior applications heretofore referred to and as conventionally shown by the dotted lines 36 and 37, respectively. These lines have been shown including the switch machines SMW and SME to signify that the position a particular switch machine is assuming determines whether or not a particular signal shall be permitted to clear when traffic conditions ahead of such signal are clear.

Although the distinctive frequencies for operating the various distinctively tuned reed type relays or indicators shown may be obtained from generators of the usual construction, it is deemed more expedient to obtain these frequencies from tuned interrupters each of which is tuned to correspond to the tuning of the selective frequency responsive relay in the tower for which it is to generate alternating current. Referring to Fig. 4 a combined interrupter and transformer for obtaining a distinctive frequency has been shown. This device comprises a closed core 30, constructed of laminated transformer iron containing a primary winding P and a secondary winding S. This coil 30 is provided with 2 projecting legs 30^a and 30^b, to the leg 30^a of which is fastened the tuned armature 31.

This armature 31 is supported by a spring 32 secured to the leg 30^a in any suitable manner, as by screws 33. A contact spring 34 is riveted to the armature 31 in such a manner that the contact spring normally engages the stationary contact 35, illustrated conventionally in the form of an arrow. The stiffness of the springs 32 and 34 and the weight of the armature 31 are such, that the natural period of vibration of the armature corresponds to the natural periods of vibration of the indicating relay which the particular interrupter is intended to operate by supplying current thereto. The armature 31 is preferably constructed of soft iron, and in this respect is different from the tuned reed 13 of the indicator for which it is to generate alternating current, in that the tuned reed 13 preferably comprises a permanent magnet. It may be pointed out in this connection that if the reed 13 of the indicating device were constructed of soft iron it would be attracted twice for each cycle of alternating current, and for this reason it would not respond unless the natural period of vibration of the armature of the indicator were twice that of the natural period of vibration of the armature of the corresponding interrupter. Since, however, the interrupter in practice is supplied with direct current the armature 31 of such interrupter may constitute either a permanent magnet or a piece of soft iron.

Although the various indicators and interrupters shown in Fig. 1 of the drawings may be grouped in series or in multiple, or in any combination of series and multiple groups, all of these indicators and interrupters have for convenience been shown connected in series in a circuit which may be traced as follows:—beginning at the winding of the indicator 8I, wire 43, winding of the indicator 7I, wire 44, winding of the indicator 7DI, wire 45, winding of the indicator 1I, wire 46, winding of the indicator 2DI, wire 47, winding of the indicator 2I, wire 48, secondary winding S of the interrupter 7R, wire 49, secondary winding S of the interrupter 7DR, wire 50, secondary winding S of the interrupter 1R, wire 51, secondary winding S of the interrupter 8R, wire 52, secondary winding S of the interrupter 2DT, wire 53, secondary winding S of the interrupter 2R, wire 54 to the common return wire C, wire 55, back to the coil of the indicator 8I.

Since, as was heretofore pointed out each of the various indicators and its corresponding interrupter, having the same prefix number, have their reeds tuned to the same natural period of vibration, and since the winding of each indicator has a condenser connected in multiple therewith of a ca-

pacity so that its winding is electrically tuned to a potential resonance of the same frequency as the period of vibration of its reed, these various indicators will very selectively respond to that particular frequency, and therefore a very large number of these indicators may be connected in series in the same line circuit and may either separately or in groups operating in overlapped relation distinctly indicate whether their respective interrupters are operating or not.

In this connection it may be pointed out that by reason of this tuning of the coil of each indicator the control current flowing in such winding predominates over all other currents flowing therein, so that, not only does the reed respond because the control current falls in step with its vibration but further because this control current is greater in value. Also, since the amplitude of vibration is cumulative, when current of the proper frequency flows in the coil of an indicator, the frequency of the current being in step with the vibration of the reed, the spring 32 can be made stiff enough so that the associated armature will not be materially attracted by current of another frequency flowing in such coil, and this is done in practice. Further, the impedances of the secondary coils S of the various induction coils is so low that all of the various frequencies of current can readily flow therethrough.

Instead of giving a plurality of distinctive indications over the same circuit by having the operator observe which reeds are vibrating at an appreciable amplitude, a more arrestive indication may be given by the provision of circuit closing means which either intermittently or continuously closes a circuit so long as the associated reed is vibrating at an amplitude of a predetermined degree. In Fig. 5 of the drawing an arrangement of this kind has been illustrated in which the reed 13^b has a spring contact finger 65 riveted thereto, which contact upon vibration of this reed 13^b to a predetermined amplitude will engage the stationary contact 66 illustrated in the form of an arrow, and effect illumination of the lamp 67 by completing a circuit connected to the terminals B and C of a suitable source of energy. Suitable audible signaling means, such as disclosed in my prior application above referred to, also may, if desired, be employed for calling the train dispatcher's attention to a change in the status of train locations and the OS indicators visually indicating such locations.

In the particular arrangement shown, see for instance the circuit for the interrupter 2DR, the secondary coil S of such interrupter is normally shunted by the front contact 57 of the track relay 2DT controlling

- the same, so that the impedances of the coils S of such interrupters are normally not contained in the line circuit. Referring now to the track relay 8T which controls the 5 interrupter 8R, this track relay 8T is de-energized, as shown in the drawings, because there is a train 60, shown conventionally, occupying the siding and the track circuit containing this relay 8T. With the relay 10 8T de-energized the back contact 61 of this relay closes a circuit for the primary winding P of the interrupter 8R. The flow of current in this circuit will instantly attract the armature 31 and thereby open the circuit 15 at the contacts 34—35, so that the armature 31 is again magnetically released to again complete this circuit. Repeated attractions of this kind will, of course, cause the armature 31 to vibrate in accordance 20 with the natural period of vibration thereof, and will cause an alternating current voltage to be generated in the secondary winding S thereof, which will cause the flow of a current of a frequency which will 25 vibrate the armature 13 of the indicator 8I, such vibration being conventionally illustrated by the multiplicity of reed ends shown in the opening of the indicator 8I in the dispatcher's office DO. In this same way 30 any number of these indicators shown in the office DO may be vibrated if currents of the proper distinctive frequencies flow simultaneously in the line circuit heretofore traced. Although the various secondary 35 windings S have been shown normally shunted by contacts 57, it is desired to be understood that this feature is not essential to the working of the system, and that these contacts 57 may be omitted, if desired. 40 In view of the fact that a train 60 has been shown, and that the manner in which the presence of this train is indicated to the dispatcher in the tower DO by vibration of the reed of indicator 8I has been 45 pointed out, it is deemed unnecessary to describe the operation of the system. It may, however, be pointed out briefly how trains may be dispatched over the railway system in a general way. For instance, let us assume 50 that the dispatcher wishes this train 60 to proceed in an easterly direction, he will move the lever LE to the left hand position thereby operating the switch machine SME to the siding position through 55 the medium of the control relay ZE, all in a manner as described in my prior application. With the control relay ZE energized to the take siding position and the switch machine SME operated to the take siding position the dwarf signal 2D will 60 clear if traffic conditions in advance are clear, and the train 60 may proceed easterly into the single track section. The dispatcher at the tower will observe the indicators 8I, 2DI and 2I and as these indica- 65 tors will be vibrated in succession but in overlapped relation, the dispatcher is informed as to the progress of the train. Although only a limited number of indicators have been shown, it is desired to be understood that the occupancy of any and all track circuits of the railway system may be indicated by such indicators, and that the indicators may also be used for indicating the positions the switch machine 70 SME and SMW are assuming at any particular time. Although only one passing siding of a railway system has been shown in the drawings and means for indicating occupancy or non-occupancy of the track circuits thereof has been shown, it is desired to be understood that in practice the same idea may, if desired, be applied to all the track circuits of the various sidings and the single track sections connecting the same, so 75 that the train dispatcher is always informed as to the location and progress of trains under his control. 80 Having thus shown and described a rather specific embodiment of the present invention, and having shown certain portions thereof rather specifically and having shown other parts conventionally, it is desired to be understood that the particular devices illustrated and the particular circuit arrangement in which they have been shown 85 have been selected for the purpose of describing the invention rather than showing the scope thereof or the specific construction preferably employed in practicing 90 the invention; and it is further desired to be understood that various changes, modifications and additions may be made to adapt the invention to the particular problems encountered in practicing the invention 95 all without departing from the spirit or scope of the invention or the idea of means underlying the same, except as demanded by the scope of the following claims. 100
- What I claim is:—
1. In a train dispatching system, the combination with a railway track divided into a plurality of track sections by insulating joints, a track circuit for each section including a source of energy and a track relay, a local train dispatcher's office, a plurality of indicators at said office each responsive to alternating current having a frequency distinctive from the frequency any other indicator will respond to, a line circuit, a source of alternating current of distinctive frequency at each track section location, and means for feeding alternating current from any one of said sources into said line circuit for rendering the corresponding one of said indicators responsive. 110
2. In a train dispatching system, the combination with a railway track divided into a plurality of track sections by insulating joints, a track circuit for each section in- 120
- 125
- 130

cluding a source of energy and a track relay, a local train dispatcher's office, a miniature track lay-out in said office, a selective frequency responsive indicator for each of said track relays located with respect to said miniature track lay-out in the same way as the corresponding track circuit is associated with said railway track, a source of alternating current at each track relay of a frequency the same as that to which the corresponding indicator at the office will respond, and a single line circuit for connecting all of said indicators and all of said sources of alternating current.

3. In a train dispatching system, the combination with a railway track divided into a plurality of track sections by insulating joints, a track circuit for each section including a source of energy and a track relay, a local train dispatcher's office, a miniature track lay-out in said office, a selective frequency responsive indicator for each of said track relays, located with respect to said miniature track lay-out in the same way as the corresponding track circuit is associated with said railway track, a source of alternating current at each track relay of a frequency the same as that to which the corresponding indicator at the dispatcher's office will respond, a single line circuit to which all of said indicators are connected, and means for connecting the source of alternating current located at a particular track relay to said line circuit when said track relay assumes a certain condition.

4. In a train dispatching system, the combination with a railway track divided into a plurality of track sections by insulating joints, a track circuit for each section including a source of energy and a track relay, a local train dispatcher's office, an indicating device in said office including a mechanically tuned reed and a coil for electro-magnetically vibrating said reed of which the reed is mechanically and the coil is electrically tuned to the same frequency, and means for energizing the coil of said indicator by an alternating current source of the same frequency and located at said track relay when one of said sections is occupied.

5. In a train dispatching system, the combination with a railway track divided into a plurality of track sections by insulating joints, a track circuit for each section including a source of current and a track relay, a local train dispatcher's office, a plurality of indicating devices in said office each including a mechanically tuned reed and a coil for electro-magnetically vibrating said reed, of each device of which the reed is mechanically tuned to a certain frequency and the coil is electrically tuned to the same frequency, and a tuned reed vibratory interrupter associated with each one of said track sections for generating an alternating cur-

rent of the proper frequency for the corresponding indicating device and supplying said current to all of said indicating devices when said one track section is occupied, whereby only the corresponding indicating device is rendered active in response to the transmission of one of said frequencies.

6. In a train dispatching system, the combination with a railway track divided into a plurality of track sections by insulating joints, a track circuit for each section including a track relay and a source of current a local dispatcher's office, an indicator for each of said sections located in said office, distinctive frequency generating means for each of said sections all connected in series in a circuit including said indicators, and means associated with each section for normally shunting the corresponding generating means and for removing such shunt and rendering such generating means active when such section is occupied by a train.

7. In a train dispatching system, the combination with a railway track divided into a plurality of track sections by insulating joints, a track circuit for each section including a track relay and a source of current, a local dispatcher's office, an indicator for each of said sections located in said office connected in series and each tuned to potential resonance to a particular frequency, distinctive frequency generating means for each of said sections all connected in series in a circuit including said indicators, and means associated with each section for normally shunting the corresponding generating means and for removing such shunt and rendering such generating means active when such section is occupied by a train.

8. In a train dispatching system, the combination with a railway track divided into a plurality of track sections by insulating joints, a track circuit for each section including a track relay and a source of current, a local dispatcher's office, and indicator for each of said sections located in said office connected in series and each comprising a coil tuned to potential resonance for a particular frequency and a reed mechanically tuned to the same frequency, distinctive frequency generating means for each of said sections all connected in series in a circuit including said indicators, and means associated with each section for normally shunting the corresponding generating means, and for removing such shunt and rendering such generating means active when such section is occupied by a train.

9. In a train dispatching system, the combination with a railway track divided into a plurality of track sections by insulating joints, a track circuit for each section including a source of energy and a track relay, a local train dispatcher's office, a miniature track lay-out in said office, a tuned

reed indicator for each of said track relays located with respect to said miniature track lay-out in the same way as the corresponding track circuit is associated with said railway track, a source of alternating current at each track relay of a frequency the same as that to which the corresponding indicator at the office will respond, and a single line circuit for connecting all of said indicators and all of said sources of alternating current.

In testimony whereof I affix my signature.
OSCAR H. DICKE.
